UNITED STATES PATENT OFFICE.

NORMAN L. BAKER, OF PHILADELPHIA, PENNSYLVANIA, ASSIGNOR TO N. L. BAKER MANUFACTURING COMPANY, OF PHILADELPHIA, PENNSYLVANIA, A CORPORATION OF DELAWARE.

GAS-STOVE BURNER.

Application filed December 23, 1920. Serial No. 432,638.

To all whom it may concern:

Be it known that I, NORMAN L. BAKER, a citizen of the United States, and resident of Philadelphia, Pennsylvania, have invented 5 certain new and useful Improvements in Gas-Stove Burners, of which the following is a specification.

My invention concerns means for preventing the flame of a gas range from being put out by a draft of air or by flooding 10 with liquid due to the boiling over of the vessels in which material is being cooked, the invention insuring the maintenance of some of the jets or flames to act as a pilot 15 light for lighting up the burner, should a portion of it be put out from any cause.

In the accompanying drawing Fig. 1 is a plan view of a burner with my invention in place.

20 Fig. 2 is a sectional view, and Fig. 3 is a perspective view.

The device consists of a tubular member 1 preferably cylindrical in shape and of small diameter as compared with the usual 25 diameter of cooking vessels. It is notched at its lower edge at 2 so that it may be fitted to a gas burner having radiating arms. It has upper notches which will allow communication between the interior of the device 30 and the exterior so that the interior flames may act as pilots to light up the portion of the burner surrounding the device should this go out from any cause.

One cause is flooding by reason of the liquid contents of cooking vessels boiling 35 over. If this occurs the device being of smaller diameter than the cooking vessel will shield the flames within it from the liquid which falls down outside of the same and this liquid will not reach the center 40 flames which will be maintained.

The device is made from a flat plate stamped out with the notches, and then rolled to cylindrical form, with its edges overlapping and held together by tongues 45 on one fitting in openings of the other edge. The device can be applied to existing forms of burners.

It will be understood that the tubular member or guard may be formed as a part 50 of the burner. Further, the burner may be of different form from that shown. Its radiating arms may be omitted and the gas jet openings may lie only within the circuit of the guard ring or flange. 55

I claim:

In combination with a gas stove burner, a shield of less diameter than the extreme diameter of the flame arising from the said burner supported thereon, and adapted to 60 protect the center jets of flame of said burner from air drafts or from flooding by liquid falling from the cooking vessels.

In testimony whereof, I affix my signature.

NORMAN L. BAKER.
